(57) **CLAIM**

The ornamental design for a protective cover for a mixer, as shown and described.

DESCRIPTION

FIG. 1 is a perspective view of a first embodiment of a protective cover for a mixer;

FIG. 2 is another perspective view of the protective cover for a mixer;

FIG. 3 is an end view of the protective cover for a mixer;

FIG. 4 is another end view of the protective cover for a mixer;

FIG. 5 is a top view of the protective cover for a mixer;

FIG. 6 is a bottom view of the protective cover for a mixer;

FIG. 7 is a side view of the protective cover for a mixer;

FIG. 8 is another side view of the protective cover for a mixer;

FIG. 9 is a perspective view of a second embodiment of a protective cover for a mixer, which is a mirror image of the protective cover of the first embodiment;

FIG. 10 is another perspective view of the protective cover for a mixer;

FIG. 11 is an end view of the protective cover for a mixer;

FIG. 12 is another end view of the protective cover for a mixer;

FIG. 13 is a top view of the protective cover for a mixer;

FIG. 14 is a bottom view of the protective cover for a mixer;

FIG. 15 is a side view of the protective cover for a mixer;

and,
FIG. 16 is another side view of the protective cover for a mixer.

The portions of the protective cover shown in dashed broken lines form no part of the claimed design.
